UNITED STATES PATENT OFFICE

PAUL F. C. WILCKE, OF SEATTLE, WASHINGTON

MECHANICAL TRAY LOADER

Application filed May 8, 1929. Serial No. 361,443.

My invention relates to an improvement in machinery playing a part in canning and preserving, and is particularly intended to eliminate the laborious, tedious and expensive loading of receptacles, such as cans, by hand into a tray or like receiver, prior to their passing into the retort for processing.

Heretofore, except as my former application for patent, Serial No. 190,418, filed May 10, 1927, patented May 7, 1929, No. 1,711,820, showed a mechanical aid to loading, trays were loaded by an operator who picked up each can and placed it in a tray. The transfer from the can delivery means to the tray 15 was purely manual, and required the constant attendance of an operator. When a tray had been thus loaded, two men were required to stack the heavily loaded tray upon others previously loaded, often as high as 20 five or six feet.

My former device, shown in the application referred to above, eliminated the heavy lifting, and to a lesser degree the manual placing of the cans within the tray. However 25 it required the constant attention of an operator to direct the individual cans to their proper places. My present invention eliminates the necessity of close attention of the operator, in that it includes means for collecting a number of cans, without attention by the operator, whereupon they are advanced all at one time, and in the relative positions they will eventually occupy in the tray. Thus a plurality of cans may be received from the feeding or depositing means, 30 and properly collected, preferably being aligned in rows, and may be then advanced as a complete row within the influence of a grouping means, by which means eventually 35 a sufficient number of cans to fill a tray is grouped in proper position, the entire group being then let down into a tray.

It is the primary object of my invention, then, to provide means of the general character described, wherein the cans are auto-

matically collected in rows, and then advanced, under the control of the operator, each row pushing forward the rows previously collected, until eventually the group fills a frame positioned immediately above 50 a tray, whereupon the bottom or platform on which the cans rest is withdrawn, permitting the cans to drop, without change of position relative to each other, into the tray.

A further object is the simplification of 55 means for collecting and transferring a small number of cans, as a single row, laterally, whether associated with a tray-loading mechanism or any other type of mechanism.

A further object is the provision of power 60 driven means for controlling the various parts of the tray loader, to relieve the operator of the strain of lifting and moving about heavy parts, and loaded trays, and to 65 speed up the operation of the device.

Other objects, and particularly those which pertain more directly to mechanical details of construction, may be understood from a study of the attached drawings, of the present specification, and the claims which terminate 70 the same.

My invention comprises the novel parts, and the novel combination and arrangement thereof, as shown in the accompanying drawings, described in the specification, and as 75 more particularly defined by the claims which terminate the same.

In the accompanying drawings I have shown my invention embodied in a form 80 which is now preferred by me.

Figure 1 is a plan view of my device.

Figure 2 is a rear side elevation of the device.

Figure 3 is a side elevation of the device, 85 taken at right angles to Figure 2.

Figure 4 is a detail in section, showing parts moving to advance the cans.

Figure 5 is a section on line 5-5 of Figure 2, showing a detail of the can-receiving and 90 collecting mechanism.

In the retorting or processing of canned goods, particularly canned fish, trays 9 of strap iron provide receptacles in the nature of open-work baskets to receive a large group of cans, the number depending upon the size. Trays thus loaded with cans are stacked one upon another, and are supported upon skeleton cars 90 running upon tracks 91 into a retort.

- 10 According to my invention, cans, generally designated by the letter C, are moved into position on a platform 1, immediately over the position they would occupy in the tray 9, and when the entire load is grouped or 15 formed, the platform is withdrawn, to drop the cans into the tray. The cans are deposited upon the platform from a delivery means, in the main consisting of four inclined angle bars 2 (see Figure 5) suitably positioned relative to one another, as by bands 20, and pivotally connecting at 21 to a hanger 22, which is supported by a rope 23 and counterweight 24. By means of the pivotal connection at 21 the angle of the chute 25 members 2 will adjust itself to the height of the platform 1, and the connection to this 30 platform is positively secured by mounting rollers 25 and 26 upon the hanger 22, these rollers 25 and 26 embracing a guide rod 30, forming part of the frame, generally designated by the numeral 3, which supports the 35 platform 1. The pivot 21 is coaxial with, or coincides with, the axis of the upper rollers 25, and cans passing singly down the chute 2 are received upon the platform 1, or more correctly speaking, upon a belt 4 moving over the platform, and passing over pulleys 40 and 41, which belt is driven continuously to advance the cans to the far side of 40 the platform 1. The chute members 2 may be so arranged as to give the can a quarter turn, that is, to bring it from a rolling position into position to slide on its end, this being well known in the art.
- 45 The frame, generally designated by the numeral 3, in effect defines and coincides with three of the sides of the tray 9 immediately therebelow. It comprises the supporting members 31, whereon may be journaled the 50 rollers 32 which support and carry the platform 1, and supported by brackets 33 thereabove are the side plates 34 at the sides and forward end of the frame. These plates 34 correspond with the position of the sides and 55 forward end of the basket or tray 9. The supporting members 31 may extend somewhat beyond the rear side of the tray, and to this extension may be connected supporting ropes 35. Like ropes 36 may be connected at the forward end of the frame 3. The frame is prevented from racking and twisting, and guided for vertical movement, by upright posts or stanchions 37, which are embraced by eyes 38 carried by the frame 3. Inclined members 39 project downwardly from the

members 31, and engage the sides of the tray 9 to position the tray properly beneath the frame.

To collect the cans which are deposited by the chute 2 upon the platform 1, I provide two plates 5 and 50. These plates are so spaced as to form a channel wide enough for one can only, and extending on opposite sides of the belt 4, so that cans deposited by the chute upon the belt 4 running over the platform 1 are carried by the belt between the plates 5 and 50 until they are lined up in a row. Now means are provided to advance these plates, pushing the cans in front of the plate 5 and raising the plate 50 out of the way, so that the cans are pushed off of the belt 4 laterally, and along the platform 1, pushing in front of them the cans which have been previously advanced and grouped on the platform over the tray space, and the plate 50 being so controlled that it will clear the row of cans which has been just advanced upon its return to its normal position.

A U-frame, consisting of the members 51, pivoted upon the frame 3 at 52, and connected by a cross-bar 53, may be rocked by means of a lever 54, or otherwise. Links or brackets 55 connect the cross-bar 53 with the plate 5. Advance of the plate 5 by swinging the lever 54 over to the right, as seen in Figures 3 and 4, pushes the cans which have been collected and aligned in a row, forward into the space on the platform above the tray. At this time an angularly disposed end 56 on the plate 5 prevents entrance of further cans from the chute 2 into the collecting space or channel.

The plate 50, which rests upon the platform 1 in advance of the belt, is carried at the end of links 57, supported from the brackets 55. These links 57 ride normally upon a cut away edge 58 of the frame 3, but upon the advance, due to swinging of the lever 54, the links 57 ride up an incline 59 of the frame 3, and the plate 50 is thereby elevated to remove it from in front of the row of cans being advanced on the platform 1. The cans are advanced sufficiently, so that when the plates move back to their normal position the plate 50 will clear the top edges of the cans which have been just advanced. A forwardly directed flange 56' opposite the flange 56 serves as a stop to position the cans at this end of the receiving and collecting channel, defined by the plates 5 and 50, and lies just inward of the side plate 34 of the frame 3, as may be seen best in Figure 1.

It is believed that the operation of the device will now be clear. From the chute 2 cans are deposited upon the platform 1, or upon the belt 4 which is simply a means of advancing them to the far end of the channel formed between the plates 5 and 50. As soon as enough cans to complete a row have collected in this channel, the operator swings the lever 54 over, advancing the row of cans, and then

returning parts to the normal position ready to receive a new row of cans. The cans as they advance are grouped by the side plates 34 of the frame, and push ahead of them the 5 rows of cans previously advanced from the collecting channel. When the entire space on the platform above a tray 9, or so much thereof as the operator considers sufficient, has been filled with cans, the platform is with- 10 drawn laterally from beneath the cans. A pinion 11 on a shaft meshing with a rack 10 secured beneath the platform 1 is shown as the means for accomplishing this movement of the platform. Rollers 13, engaging the 15 upper face of the platform immediately above the shaft 12, serve to hold the platform down upon the rollers 32 of the frame, by means of which it is supported. The cans now drop over the edge of the platform 1 into the tray 20 immediately therebelow, without disturbance of their positions relative to one another. When a tray has been thus loaded, the entire device may be lifted, another tray positioned on the tops of the cans in the tray just loaded, 25 and the device dropped, the members 39 engaging the sides of the tray and properly positioning it, whereupon the platform is run out over the new tray, and cans are again collected and advanced to be grouped, as before. 30 Preferably, owing to the heavy weights and considerable resistance of the parts, power means are provided for doing the heavy work of lifting the device and removing the platform. Thus, a shaft 6 overhead may carry 35 drums 60 and 61, over which the supporting ropes 35 and 36 are wound in opposite directions, and a clutch (not shown) provides for application of power to this winding or reeling mechanism to lift the entire device, at 40 such times as this is required. The stanchions 37 guide the device, and retain it in proper position relative to the car 90. For driving the pulley 41 a vertical shaft 42 may be employed, this having a feather connection with 45 a bevel gear 43, meshing with a gear 44 on the shaft that carries the pulley 41. The feather connection of the pinion 43 to its shaft permits the pinion to slide vertically, as the entire device is lifted or lowered. The 50 shaft carrying the pinion 44 and the pulley 41 may be supported from the projecting ends of the transverse guides 30, as is best seen in Figure 1. 55 Similarly, power means may be employed to withdraw the platform 1, and for this purpose a vertical shaft 14 may be employed, this carrying a pinion 15, which is slidable along the shaft 14, and which meshes with a gear 60 16 upon the cross shaft 12 which carries the pinions 11. Obviously, these operations might be done by hand, but I prefer the power means, and these two additional vertical shafts 14 and 42 serve an additional purpose 65 in steadying the rear end of the machine,

being supported in thrust bearings 17 for this purpose.

What I claim as my invention is:

1. In a tray loader, in combination, a frame defining three sides of a rectangle, means for aligning said frame with three sides of a tray, positioned therebelow, to be loaded, a platform adapted to be positioned beneath said frame and above the tray, said frame having guides permitting lateral withdrawal of the platform, and means for depositing individual cans upon said platform, and a pair of spaced plates located without the confines of the tray and above the platform for collecting a plurality of cans thus deposited, means for advancing said plates to advance the collected cans over the platform into the space above the tray, and means for withdrawing the platform in a direction opposite the can's advance, to permit the cans thus grouped within the frame to drop into the tray therebelow the forward plate engaging the cans to retain them in advanced position while said platform is being withdrawn. 70
2. In a tray loader, in combination, a frame, means for supporting the frame above the tray, means guiding said frame for vertical movement, a platform supported in said frame, means for delivering cans thereupon, 80 means for aligning the individual cans in rows, and means for producing relative lateral movement of the platform and cans supported thereon to drop the cans into a tray positioned therebelow. 85
3. In a tray loader, in combination, a frame, means for supporting the frame above the tray, means guiding said frame for vertical movement comprising vertical shafts, one of which is power-driven, a platform supported in said frame, means for delivering cans thereupon, 90 means for aligning the individual cans in rows, and means driven from said driven shaft for producing relative lateral movement of the platform and cans supported thereon to drop the cans into a tray positioned therebelow. 95
4. In a tray loader, in combination, a frame, a platform supported in said frame for transverse movement, means for supporting the frame at different levels, vertical guide means for said frame comprising vertical shafts, one of which is power-driven, means including a transverse belt for delivering cans upon said platform, means for aligning the individual cans in rows, means for withdrawing said platform laterally from under the cans, thereby allowing the cans to drop into a tray positioned below the platform, and means driven from said driven shaft for advancing said belt. 115
5. In a tray loader, in combination, a platform, means for depositing individual cans on end upon said platform, spaced front and rear guide plates receiving the cans thus deposited to align them in a row, a link, piv- 120
- 125
- 130

totally connecting said front and rear guide plates, means connectively secured to the rear plate for shifting the two plates laterally to advance the row of cans thereover, and cam means fixedly positioned in advance of the front plate and directly engaged by said link to lift it and said forward plate during such advance, to permit the cans to move beneath it, and be advanced to a location where the forward or raised plate will clear them upon its return movement.

Signed at Seattle, Washington, this 23rd day of April, 1929.

PAUL F. C. WILCKE.
